Primary Examiner — Prabhakar Deshmukh(74) Attorney, Agent, or Firm — Optima Law Group, APC(57) CLAIM

The ornamental design for a game score card, as shown and described.

DESCRIPTION

FIG. 1 is a front view of a game score card showing my new design.

The word GLORY embedded on all four sides of the word card forming part of the claimed design has been filed as a trademark and is pending registration for Darryl K. Reid.
